UNITED STATES PATENT OFFICE.

WILLIAM H. FULPER, OF FLEMINGTON, NEW JERSEY.

DESIGN FOR A STATUETTE OR SIMILAR ARTICLE.

Application filed January 17, 1923. Serial No. 4,899. Term of patent 3½ years.

To all whom it may concern:

Be it known that I, WILLIAM H. FULPER, a citizen of the United States of America, and resident of Flemington, county of Hunterdon, and State of New Jersey, have invented a certain new, original, and ornamental Design for a Statuette or Similar Article, of which the following is a specification, reference being had to the accompanying drawings, forming part thereof.

In the drawing, Figure 1 is a front elevation of a statuette constituting the design; and

I claim:

The ornamental design for a statuette or similar article, as shown.

WILLIAM H. FULPER.
